UNITED STATES PATENT OFFICE.

BENSON S. BULLIS, OF ST. LOUIS, MISSOURI, ASSIGNOR, BY MESNE ASSIGNMENTS, OF ONE-HALF TO DUDLEY SHEPPARD, OF ST. LOUIS, MISSOURI.

WINDOW-SCREEN.

SPECIFICATION forming part of Letters Patent No. 723,824, dated March 31, 1903.
Application filed December 2, 1901. Serial No. 84,369. (No model.)

To all whom it may concern:

Be it known that I, BENSON S. BULLIS, a citizen of the United States, residing at the city of St. Louis, State of Missouri, have invented 5 a certain new and useful Improvement in Window-Screens, of which the following is a full, clear, and exact description, such as will enable others skilled in the art to which it appertains to make and use the same, reference being had to the accompanying drawings, forming part of this specification, in which—

my invention consists in the various matters 50 hereinafter described and claimed.

Referring now more particularly to the drawings, 1 represents the window frame or casing; 2, the inner sash; 3, the outer sash; 4, the sill, and 5 the top bar of the frame. 55 Screens 6 and 7 are connected to the outer sash in such manner that the openings between the sash and the sill or the sash and the said top bar are protected by said screens in all positions of the sash. Said screens are 60

mounted upon rollers 8, which are carried by frames each of which comprises a top strip 9 and end brackets 10 and 11, by which the rollers are supported. Thus a roller with its screen can be readily mounted upon one of 65 said frames and the frame then fastened in position, thereby avoiding the difficulty of mounting a roller itself in a small space or at a point difficult of access. In the embodiment of my invention here illustrated one 70 roller-frame is secured to the top bar 5 of the window-easing, and the lower edge of the screen carried by said roller is fastened to the upper rail 12 of the outer sash, while another of said roller-frames is secured to the 75 under face of the lower sash-rail 13, the free end of the screen being provided with a strip 14, which has buttons or the like 15, adapted to be received by eyebolts 16, fastened to the sill 4. In order to provide for readily 80 fastening the roller-frame upon the sash-rail 13, said rail is provided with turn-hooks 17, which when turned into one position enter slots 18 in the opposite sides of the frame-strip 9 as said strip is moved into position 85 against the sash-rail, and when said hooks are turned to bring their angle-fingers 19 under the strip 9 the frame is firmly but removably secured. The frames being mounted in the manner described and the rollers having 90 springs of usual type under constant tension, it will be apparent that as the sash 3 is raised or lowered one screen is unwound to protect the space between the sash and the window-frame while the other screen is wound upon 95 its roller.

35 My invention relates to improvements in window-screens, my objects being to provide a bracket for the dog-carrying end of the roller of such construction that spring-rollers of usual type can be employed and the dogs 40 effectively held out of engagement with the notches in the end of the usual spring-actuated rod, to provide means for readily mounting the screens upon the sash or the window-frame, and to provide an apron or flap which 45 effectively covers the space between the roller and its supporting-bar, but causes little wear of the screen.

To these ends and also to improve generally upon devices of the character indicated

Manifestly a slight space must be left between a roller and the strip 9 or other frame.

member below which said roller is supported, and in order to protect this space an apron or flap 20, of screen-cloth or other suitable material, is attached to the strip 9 over about 5 the longitudinal axis of the roller and depends upon the cloth upon said roller. A light strip 21, of wood or the like, is provided upon the free edge of the apron and serves to weight said edge sufficiently to hold 10 it upon the wound cloth, thus causing the apron to effectually protect the space, and said strip also prevents the free edge of the apron from wrinkling and thereby forming openings for flies and other insects. The 15 apron being suspended as described and being flexible readily falls upon the side of the roller toward which said roller is being rotated, and thus exerts but little wear upon the screen as it is being wound or unwound. 20 The roller has projecting from one end the usual spring-actuated rod 22, in whose projecting end are formed the customary notches 23 for the dogs 24, while the other end of the roller is provided with an opening 25. The 25 said notches are in the sides of the rod and have their ends open. One of the brackets (the bracket 10) upon the roller-frame has a pin 26, which enters said opening 25, while the bracket 11 has upon its inner face two 30 inwardly-projecting pins 27, which snugly enter the notches 23 in the spring-actuated rod, thus firmly holding said rod against rotation and preventing the dogs 24 from entering 35 said notches. The outer portions of the pins 27 are smoothed and rounded in order to insure easy passage of the dogs over the same. I am aware that many minor changes in the construction, arrangement, and combination 40 of the several parts of my device can be made and substituted for those herein shown

and described without in the least departing from the nature and principle of my invention.

Having thus described my invention, what I claim as new, and desire to secure by Letters 45 Patent, is—

1. The combination with a spring-roller having dogs and a rod provided with notches, of a bracket having projecting members adapted to seat in said notches, the outer surfaces of said projecting members being formed to lie flush with the exterior surface of the roller-rod to constitute a smooth unbroken surface, substantially as and for the purpose described. 55

2. The combination with a spring-roller having dogs and a rod provided with notches, of a bracket, oppositely-arranged fingers 27 projecting outwardly from the bracket adapted to seat in said notches, the outer surfaces 6c of said fingers being formed to lie flush with the exterior surface of the roller-rod to constitute a smooth unbroken cylindrical surface, substantially as described.

3. The combination with a spring-roller 65 having dogs and a rod provided with a notch, of a rigid projection adapted to seat in said notch, the outer surface of said projection being formed to lie flush with the exterior surface of the roller-rod to constitute a smooth 70 unbroken surface, substantially as and for the purpose described.

In testimony whereof I hereunto affix my signature, in the presence of two witnesses, this 29th day of November, 1901.

BENSON S. BULLIS.
